10 Claims. (Cl. 250—83.6)

1
This invention relates to apparatus for testing Geiger tubes and more particularly to apparatus for providing a fast and reliable determination of the response characteristic of a Geiger tube. The invention is especially adapted to provide an instantaneous indication of the voltage at which a predetermined Geiger tube response occurs.

In general, Geiger tubes have a hollow conductive casing which is filled with a suitable gas, and a wire axially disposed within the casing and insulated from the casing. The casing serves as the cathode and the wire as the anode of the Geiger counter. When a radioactive emanation penetrates the tube, some of the gas molecules in the tube are ionized and the ions are collected by the cathode and the anode to form a current through the tube. When the voltage between the anode and cathode is relatively low, the current changes considerably with small changes in voltage. At higher voltages, the current changes only slightly with changes in voltage. This saturated region, designated as the plateau region, usually serves as the operating portion of the tube.

The response characteristics of a particular tube may change with time because of aging of the gas in the tube and because of changes in the gas temperature and pressure. In other words, the current through the Geiger tube may vary at different times even though the voltage on the tube remains constant. Thus, if a constant current having a predetermined value in the plateau region is desired for purposes of calibration, such as for calibrating other equipment used with Geiger tubes, the current cannot be obtained by maintaining the voltage on the tube constant.

This invention provides apparatus for regulating the current through a Geiger tube by automatically varying the voltage applied between the anode and cathode of the tube. The invention also provides apparatus for instantaneously indicating the voltage required to obtain the particular current.

An object of this invention is to provide apparatus for regulating the current through a Geiger tube.

Another object is to provide apparatus of the above indicated character for instantaneously and reliably calibrating a Geiger tube.

A further object is to provide apparatus of the above indicated character for maintaining the current through a Geiger tube substantially constant by automatically varying the voltage on the tube.

2
Still another object is to provide apparatus of the above indicated character for instantaneously indicating the voltage required to maintain a substantially constant current through a Geiger tube.

A still further object is to provide apparatus of the above indicated character which is simple, compact, efficient and reliable.

Other objects and advantages of the invention will be apparent from a detailed description of the invention and from the appended drawings and claims.

In the drawings the single figure is a circuit diagram of one embodiment of the invention.

15 Referring to the drawings, a Geiger tube, generally indicated at 10, is provided. The tube 10 has a grounded conductive casing 12, which is filled with a suitable gas such as argon, and a wire 14 which is axially disposed within the casing in insulated relationship to the casing. The wire 14 is connected through a relatively high resistance 16 to a power supply which will be described in detail hereinafter and is also connected through a coupling capacitance 18 to the grid of a tube 20. The cathode of the tube 20 is grounded through a resistance 22 and is connected to the grid through a resistance 24. The plate is supplied through a potentiometer 26 with positive voltage from a suitable power supply, such as a battery 28. The grid of a tube 30 is connected to the cathode of the tube 20; the cathode of the tube 30 is connected to a grounded resistance 32; and the plate is connected directly to the battery 28.

35 The movable arm 34 of the potentiometer 26 is connected through a coupling capacitance 36 to the grid of a tube 38. A resistance 40 is provided between the grid of the tube 38 and ground and a resistance 42 between the cathode and ground. The plate of the tube is supplied through a resistance 44 with positive voltage from the battery 28 and is coupled through a capacitance 46 to the grid of a tube 48. The grid of the tube 48 is grounded through a resistance 50 and the cathode is directly grounded. A resistance 52 is connected between the plate of the tube 48 and the battery 28.

45 A capacitance 54 couples the plate of the tube 48 to the grid of a tube 56. The grid of the tube 56 is grounded through a resistance 58 and the plate is supplied with positive voltage from the battery 28. The cathode is connected to ground through a resistance 60 and the resistance 42 in series.

55 In addition to being connected to the cathode of the tube 20, the resistance 24 is connected

through a coupling capacitance 62 to the grid of a tube 64. A resistance 66 is connected between the grid of the tube 64 and the cathode, which is grounded. The plate is supplied with positive voltage through a resistance 68 and is coupled through a capacitance 70 to the grid of a tube 72, the grid being connected to a grounded resistance 74. A resistance 76 and a capacitance 78 are provided in parallel between the cathode of the tube 72 and ground and a resistance 80 is provided between the plate of the tube and the power supply 28.

The plate of the tube 72 is coupled through a capacitance 82 to the grid of a tube 84. Resistances 86 and 88 connect the grid of the tube 84 to the power supply 28 and to ground, respectively. The cathode of the tube 84 is grounded and the plate is supplied through a resistance 90 with positive voltage from the power supply 28. Capacitances 92 and 94 connect the grid and plate of the tube 84 to the plate and grid, respectively, of a tube 96. A resistance 98 is provided in parallel with the capacitance 94 and in series with a resistance 100. The resistance 100 is in series with a suitable power supply, such as a battery 102, the positive terminal of which is grounded. The cathode of the tube 96 is grounded and positive voltage from the battery 28 is applied to the plate through a resistance 104.

A coupling capacitance 106 is connected between the plate of the tube 96 and the grid of a tube 108. A resistance 110 is provided between the grid of the tube 108 and ground and a resistance 112 between the cathode and the negative terminal of the battery 102. Positive voltage from the battery 28 is applied to the plate of the tube 108 as well as to the plate of a tube 114. The grid of the tube 114 is connected in series with resistances 116 and 118 and with the battery 102. The grid is also connected through a coupling capacitance 120 to the cathode of the tube 56.

The cathode of the tube 114 is connected to the cathode of the tube 108 and to the cathode of a diode 122, the plate of which is connected to the cathode of a diode 124. A storage capacitance 125 is connected between the cathode of the diode 124 and the resistance 118 and a resistance 126 and a capacitance 127 are provided in parallel between the capacitance and ground. The grid of a tube 128 is connected directly to the cathode of the diode 124. The plate of a diode 130 is connected to the common terminal between the capacitance 125 and the resistance 118 and the cathode of the diode 130 is connected to the plate of the diode 124. The plate of the diode 124 is also coupled by a capacitance 132 to the cathode of the tube 56.

The plate of the tube 128 is supplied with positive voltage from the battery 28 and the cathode is connected through a resistance 134 to the negative terminal of the battery 102. A resistance 136 and a parallel arrangement of diodes 138 and 140 are provided in series between the cathode of the tube 128 and ground. The cathode of the diode 138 and the plate of the diode 140 are grounded, while a resistance 142 and a meter 144 are connected in series to the plate of the diode 138 and the cathode of the diode 140. One side of the meter 144 is grounded.

The cathode of the tube 128 is also connected to a stationary contact of a single-pole, double-throw switch 146, the other stationary contact of the switch being grounded. A capacitance 148

is provided between the movable contact of the switch 146 and ground, and a meter 150, a resistance 152, a potentiometer 154, and a resistance 156 are connected in series between the movable contact of the switch 146 and the resistance 16. The resistances 156, 152 and 134 and the potentiometer 154 are chosen to provide zero voltage on the cathode of the tube 128. A capacitance 158 is connected to ground from the common terminal between the resistances 156 and 16 and a capacitance 160 is connected between the movable contact 162 of the potentiometer 154 and the common terminal between the resistances 156 and 16.

The movable contact 162 of the potentiometer 154 is connected to the grid of a tube 164. The cathode of the tube 164 is connected to the movable contact 166 of a grounded potentiometer 168, which is connected to the positive terminal of a regulated power supply, such as a battery 170, adapted to supply a less positive voltage than the battery 28.

The plate of the tube 164 is connected through a resistance 176 to the grid of a tube 178 and through a resistance 180 to the cathode of the tube 178. The cathode of the tube 178 is also connected to the common terminal between the resistances 156 and 16. The plate of the tube 178 is connected to a grounded filter capacitance 182 and to the cathode of a diode 184. The plate of the diode 184 is in series with a resistance 186 and the grounded secondary winding 188 of a power transformer 190.

With a source of known radioactivity acting upon the Geiger tube 10, a substantially constant number of radioactive emanations penetrate the tube. Each radioactive emanation causes some of the gas molecules to become ionized. The electrons are attracted to the wire 14 and the positive ions to the casing 12, producing on the tube a voltage pulse having an amplitude largely dependent upon the voltage difference between the wire 14 and the casing 12.

The voltage pulses on the Geiger tube 10 are amplified by a plurality of amplifier stages in cascade arrangement, including the tubes 20, 30, 38 and 48. The pulses are then introduced to the cathode follower stage which includes the tube 56. The gain of the amplifier and cathode follower stages can be varied by adjustment of the movable arm 34 of the potentiometer 26 to give an integral amplification of the voltage pulse on the Geiger tube 10. For example, with a voltage pulse of 0.35 volt on the Geiger tube, a voltage pulse of 35 volts may be produced on the cathode of the tube 56 and introduced to the plate of the diode 124.

Normally, the voltage on the plate of the diode 124 is substantially the same as the negative voltage on the cathode of the diode because of the leakage provided by the diode 130. When positive pulses are applied to the plate of the diode 124 from the cathode of the tube 56, current flows through a circuit which includes the battery 28, the tube 56, the capacitance 132, the diode 124, the capacitance 125 and the resistance 118. The current charges the capacitance 125 to a direct voltage substantially equal to the voltage on the cathode of the tube 56. This charge remains on the capacitance 125 during the intervals between successive pulses, but any charge that appears on the capacitance 132 is eliminated during pulse intervals by a discharge current which flows from the capacitance 132 through the capacitance 120, the resistance 116 and the diode 130. In this

way, the capacitance 125 is able to reach the full voltage on the cathode of the tube 56 during the time that the voltage on the cathode of the tube 56 remains constant or is increasing. For example, with -50 volts at the common terminal between the capacitance 125 and the resistance 118 and with pulses having an amplitude of 35 volts appearing on the cathode of the tube 56, the voltage on the cathode of the tube 124 is $-50 + 35 = -15$ volts. This voltage changes to $-50 + 40 = -10$ volts when the amplitude of the pulses on the cathode of the tube 56 increases to 40 volts.

To provide a decrease of the voltage across the capacitance 125 corresponding to a decrease of pulse amplitude on the cathode of the tube 56, amplifier stages, including the tubes 64 and 72, and a multivibrator, including the tubes 84 and 96, are provided. The amplified pulses from the Geiger tube 10 produce negative output signals on the plate of the tube 96 which, when introduced to the grid of the normally conducting tube 108, cause the tube 108 to become cut off. During the time that the tube 108 is conducting, a voltage is produced across the resistance 112 to bring the cathode of the tube 114 to substantially ground potential. When the tube 108 is cut off by the negative signals from the plate of the tube 96, the voltage on the cathode of the tube 114 starts to drop towards the voltage on the battery 102. Since the cathode voltage on the tube 114 follows the cathode voltage on the tube 108, the tube 114 starts to conduct when its cathode voltage approaches the negative bias on its grid.

Normally, the grid of the tube 114 is biased to a voltage substantially equal to the voltage at the common terminal between the capacitance 125 and the resistance 118—for example, -50 volts. With the positive voltage pulses introduced to the grid of the tube 114 from the cathode of the tube 56, the grid of the tube 114 becomes less negatively biased. When current flows through the tube 114, the cathode voltage follows the grid voltage and becomes dependent upon the voltage on the cathode of the tube 56. Thus, with 35 volts on the cathode of the tube 56, the voltage on the cathode of the tube 114 is $-50 + 35 = -15$ volts. If the amplitude of the pulses on the cathode of the tube 56 decreases to 30 volts, the voltage on the cathode of the tube 114 likewise decreases to $-50 + 30 = -20$ volts. However, the voltage on the cathode of the diode 124 remains at $-50 + 35 = -15$ volts because of the inability of the capacitance 125 to discharge. Since the voltage on the cathode of the tube 114 is more negative than the voltage on the cathode of the diode 124, the capacitance 125 partially discharges through a circuit which includes the capacitance 125, the diode 122, the resistance 112 and the resistance 118. The capacitance discharge continues until the voltages on the cathodes of the tubes 124 and 114 become equal. The cathode of the diode 124 therefore provides at all times an indication in direct volts of the amplitude of the pulses appearing on the cathode of the tube 56.

Since the voltage on the cathode of the tube 124, as indicated by the meter 164, follows the voltage on the cathode of the diode 124, a direct voltage proportional to the amplitude of the pulses from the Geiger tube 10 is introduced to the grid of the tube 164. Thus, if the pulse amplitudes increase, the voltage on the grid of the tube 164 increases, causing the current through the tube to increase. This produces a voltage drop on the plate of the tube 164 and on

the grid of the tube 178 and an increase in the effective resistance provided by the tube 178 in the series circuit which includes the resistance 128, the tube 184, the tube 178, the resistance 16 and the Geiger tube 10. The resultant decrease in the voltage on the Geiger tube 10 causes the amplitude of the pulses from the Geiger tube to decrease. Similarly, if the pulse amplitude decreases, the voltage on the grid of the tube 164 decreases and produces an increase in the voltage on the Geiger tube 10 so as to increase the amplitude of the Geiger tube pulses.

In operation, the movable contact of the switch 146 is first moved into engagement with the right stationary contact shown in the accompanying drawing. The arm 166 of the potentiometer is then adjusted to provide a predetermined voltage on the Geiger tube by varying the effective resistance provided by the tube 178. The movable arm 162 of the potentiometer 154, which has a relatively low resistance compared with the resistance 156, may also be adjusted to provide a relatively fine control of the voltage on the Geiger tube and of the operating voltage on the cathode of the tube 128. An adjustment may also be made of the potentiometer arm 34 to vary the gain of the amplifiers. The movable contact of the switch 146 is then rotated to the left stationary contact shown in the accompanying drawing. The circuits then operate to regulate the amplitude of the pulses from the Geiger tube by varying the voltage applied to the tube.

There is thus provided apparatus for regulating the amplitude of the current pulses which flow through a Geiger tube when radioactive emanations penetrate the tube. The apparatus operates to maintain the amplitude of the pulses substantially constant by automatically varying the voltage applied to the tube. It should be appreciated that the term "Geiger tube" as employed above and as used in the claims refers to all types of radiation detectors. For example, the term would include ionization chambers.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the invention, what I claim as new and desire to secure by Letters Patent is:

1. In combination, a Geiger tube operative to produce output pulses having amplitudes dependent upon the voltage on the tube, means for applying a variable voltage on the Geiger tube, a first tube, a second tube, a condenser, means associated with the condenser and the first and second tubes to produce across the condenser a voltage substantially proportional to the amplitude of the Geiger tube pulses, and means for varying the voltage on the Geiger tube in accordance with changes in the condenser voltage.

2. In combination, a Geiger tube operative to produce output pulses having amplitudes dependent upon the voltage on the tube, means for applying a variable voltage on the Geiger tube, a first tube, a condenser adapted to be charged by output pulses from the Geiger tube and connected to the first tube to provide a voltage proportional to the amplitude of output pulses of increasing strength, a second tube, means for producing on the second tube a voltage proportional to the amplitude of output pulses of de-

creasing strength, means connecting the condenser and the first and second tubes to produce across the condenser a voltage substantially proportional at all times to the amplitude of the Geiger tube pulses, and means for varying the voltage on the Geiger tube in accordance with changes in the condenser voltage from a predetermined value.

3. In combination, a Geiger tube adapted to provide output pulses upon the penetration of radioactive emanations, a condenser, a first tube connected to the condenser to provide a continuous circuit for charging the condenser to voltages proportional to the output pulses of increasing amplitude from the Geiger tube, a second tube connected to the condenser to provide a continuous circuit for discharging the condenser to voltages proportional to the output pulses of decreasing amplitude from the Geiger tube, and means responsive to the voltage across the condenser to vary the voltage on the Geiger tube for the maintenance of output pulses of a substantially constant amplitude from the tube.

4. In combination, a Geiger tube adapted to provide output pulses upon the penetration of radioactive emanations, a first tube, a second tube, a condenser connected to the first and second tubes, means for applying a voltage substantially proportional to the amplitude of the output pulses to the first and second tubes, means for charging the condenser through the first tube to a voltage substantially proportional to output pulses of increasing amplitude, means for discharging the condenser through the second tube to a voltage substantially proportional to output pulses of decreasing amplitude, means connected to the second tube for preventing the discharge of the condenser through the tube for output pulses of increasing amplitude, and means operative in accordance with the voltage on the condenser to vary the voltage applied to the Geiger tube so as to maintain the output pulses from the Geiger tube substantially constant in amplitude.

5. In combination, a Geiger tube operative to produce output pulses having amplitudes dependent upon the voltage on the tube, a first circuit, a second circuit, means common to the first and second circuits, the first circuit being operative in accordance with pulses of increasing amplitude from the Geiger tube to provide an indication proportionate to the pulse amplitude across the common means, the second circuit being operative in accordance with pulses of decreasing amplitude from the Geiger tube to maintain an indication proportionate to the pulse amplitude across the common means, a voltage source, a variable impedance connected to the voltage source and the Geiger tube, and means for varying the value of the impedance in accordance with the indication from the common means to maintain the amplitude of the pulses through the Geiger tube substantially constant.

6. In combination, a Geiger tube operative to produce output pulses having amplitudes dependent upon the voltage on the tube, a first circuit, a second circuit, means common to the first and second circuits, the first circuit being operative in accordance with pulses of increasing amplitude from the Geiger tube to provide an indication proportionate to the pulse amplitude across the common mean, means in the first circuit for preventing the operation of the circuit for pulses of decreasing amplitude, the second circuit being operative in accordance with pulses

5 of decreasing amplitude from the Geiger tube to maintain an indication proportionate to the pulse amplitude across the common means, means in the second circuit for preventing the operation of the circuit for pulses of increasing amplitude, a voltage source, a variable impedance connected to the voltage source and the Geiger tube, and means for varying the value of the impedance in accordance with the indication from the common means to maintain the amplitude of the pulses through the Geiger tube substantially constant.

7. In combination, a Geiger tube operative to produce output pulses having amplitudes dependent upon the voltage on the tube, a condenser, first means for charging the condenser to a value proportional to the amplitudes of the pulses from the Geiger tube when the pulse amplitudes are increasing, second means for discharging the condenser to a value proportional to the amplitudes of the pulses from the Geiger tube when the pulse amplitudes are decreasing, a voltage source, a variable impedance connecting the voltage source to the Geiger tube, and means operative in accordance with the charge on the condenser to vary the value of the variable impedance to maintain the output pulses from the Geiger tube substantially constant.

8. Apparatus for regulating the output of a Geiger tube, including, means for applying a voltage to the Geiger tube to produce output pulses in response to radioactive emanations, a condenser, means for charging the condenser in accordance with increased responses of the tube, means for preventing the condenser from discharging through the charging means during the periods of decreased response of the tube, means for discharging the condenser in accordance with decreased responses of the tube, means for preventing the condenser from charging through the discharge means during the periods of increased response of the tube, and means operative in accordance with the charge on the condenser to vary the voltage applied to the Geiger tube so as to maintain the tube current within predetermined limits.

9. Apparatus for regulating the output of a Geiger tube, including, means for applying a voltage to the Geiger tube to produce output pulses in response to radioactive emanations, a capacitance, means for introducing the output pulses to the capacitance to charge the capacitance to a value proportional to pulses of increasing amplitude, a normally conductive tube, means for cutting off the normally conductive tube during the output pulses from the Geiger tube, means operative upon the cut-off of the normally conductive tube to provide a conductive path for the discharge of the capacitance during the periods of output pulses of decreasing amplitude until the charge on the capacitance is proportional to the amplitude of the output pulses, and means operative in accordance with the charge on the capacitance to vary the voltage applied to the Geiger tube so as to maintain the amplitude of the output pulses within predetermined limits.

10. Apparatus for regulating the output of a Geiger tube, including, means for applying a voltage to the Geiger tube to produce output pulses in response to radioactive emanations, a capacitance, means for introducing the output pulses to the capacitance to charge the capacitance to a value proportional to pulses of increasing amplitude, a first tube, means for cutting off the first tube during the output pulses from the Geiger tube, a second tube associated with the first tube,

means for introducing the output pulses to the second tube for the conductance of the tube during the cut-off periods of the first tube, means for producing a discharge of the capacitance through the second tube during the conductance of the second tube for output pulses of decreasing amplitude until the charge on the capacitance is proportional to the amplitude of the output pulses, and means operative in accordance with the charge on the capacitance to vary the voltage applied to the Geiger tube so as to maintain the amplitude of the output pulses within predetermined limits.
